UNITED STATES PATENT OFFICE.

PETTIS A. REID, OF RICHMOND, INDIANA.

DESIGN FOR WIRE-FENCING FABRIC.

SPECIFICATION forming part of Design No. 35,386, dated December 3, 1901.

Application filed October 15, 1901; Serial No. 78,759. Term of patent 14 years.

To all whom it may concern:

Be it known that I, PETTIS A. REID, a citizen of the United States, residing at Richmond, in the county of Wayne and State of Indiana, have invented and produced a new, useful, and original Design for Wire-Fencing Fabrics, of which the following is a specification, reference being had to the accompanying drawings, forming a part thereof.

10 In said drawings, Figure 1 represents a front elevation of a broken-off portion or section of a wire-fencing fabric embodying my new design, and Fig. 2 is a sectional plan view of the same on the line II II of Fig. 1.

15 As shown in the drawings, the said fencing fabric is of the square-mesh type and consists of a suitable number of longitudinal or strand wires *a* and vertical or stay wires *b*, crossing the strand-wires and secured thereto at the 20 points of intersection. The said longitudinal or strand wires have short angular crimps or bends *a'* formed therein at suitable intervals, the crimps of the several wires being arranged one above another between the stays and certain series thereof being utilized as seats to 25 receive the connections for the stays or cross-

wires. Said stays have intermediate looped portions coincident with the crimps of the strands and coiled or bent closely about the said crimps, the whole giving the peculiar 30 ornamental appearance shown.

The leading or material features of my design reside in a wire-fencing fabric composed of longitudinal wires or strands having short angular crimps or bends therein at suitable 35 intervals, together with stay-wires at intervals crossing said strands and having intermediate looped portions thereof coiled closely about crimps in the strands between other crimps therein.

Having thus described my invention, what I claim as new, and desire to secure by Letters Patent of the United States, is—

The design for a wire-fencing fabric, substantially as herein shown and described. 45

In testimony whereof I have signed my name in the presence of two subscribing witnesses.

PETTIS A. REID.
